UNITED STATES PATENT OFFICE.

JULIUS BRENZINGER, OF NEW YORK, N. Y., ASSIGNOR TO THE MAX AMS MACHINE COMPANY, OF NEW YORK, N. Y., A CORPORATION OF NEW YORK.

COVER FOR JARS OR OTHER VESSELS.

SPECIFICATION forming part of Letters Patent No. 761,652, dated June 7, 1904.

Application filed November 6, 1903. Serial No. 180,006. (No model.)

To all whom it may concern:

Be it known that I, JULIUS BRENZINGER, a citizen of the United States, residing at New York city, (Manhattan,) county and State of New York, have invented new and useful Improvements in Covers for Jars or other Vessels, of which the following is a specification.

This invention relates to a cover for jars and other receptacles which forms a tight joint, is not liable to break the glass while being applied, and which may be readily opened.

In the accompanying drawings, Figure 1 is a perspective view of a jar provided with my improved cover. Fig. 2 is a vertical section through the cover before the band is upset; Fig. 3, a similar section with the band upset; Fig. 4, a detail cross-section through part of the cover.

The letter *a* represents an annular resilient band having disconnected overlapping ends, the outer one of which is provided with a finger-piece *a'*. The lower edge of the band is turned inward to form a flange *a*², while its upper edge is unbent until the band has been applied to the jar, Fig. 2. The mouth of the fragile jar *A* is closed by a cap or disk *b*, between which and the jar a flexible gasket or cushion *c* is interposed. The cap *b* is provided on its upper side and near its circumference with an annular groove *b'*.

In use the gasket *c* and cap *b* are placed in position, and then the flanged band *a* is sprung around the bottle-head *A'*, so as to embrace the latter together with the gasket and cap. As the ends of the band are disconnected this operation can be readily performed. When

the band has thus been fitted in position, its lower flange *a*² will engage the lower shoulder *A*² of the bottle-head, while its upper edge will project beyond the cap *b*, Fig. 2. This upper edge is now turned inward and downward by spinning until the flange *a*³ thus formed enters the annular groove *b'* of cap *b*, and thus forms an air-tight joint between bottle and cap, Figs. 3 and 4. During this operation the spinning-rollers will act against a resilient body—viz., the cushioned cap *b*—and not against the jar directly. In this way breakage will be prevented, which is very liable to occur when the pressure of the rollers is transmitted directly to the glass. To open the cover, the band *a* is grasped by its finger-piece *a'* and uncoiled, when the flange *a*³ will be withdrawn from the groove of the cap, and the parts will thus become readily disconnected.

What I claim is—

The method of closing a jar which consists in placing upon the jar-head, a flexible gasket and a superposed yieldingly-supported cap, surrounding the jar-head, gasket and cap by a flexible band having a lower flange, and upsetting the upper flange of the band against the yieldingly-supported cap, substantially as described.

Signed by me at New York city, (Manhattan,) New York, this 5th day of November, 1903.

JULIUS BRENZINGER.
